UNITED STATES PATENT OFFICE

2,181,956

WATER FEEDER

William J. Woolley, Chicago, Ill.

Application August 13, 1937, Serial No. 158,964

1 Claim. (Cl. 137—101)

This invention relates in general to water feeders, and more particularly to an automatic water feeder device for supplying water to low pressure steam boilers, humidifiers, expansion tanks and the like.

A principal object of the invention is the provision in a water feeder of means for automatically supplying water to a boiler or the like and for controlling and maintaining constant the water supply within the boiler at a predetermined working level.

Another important object of the invention is the provision of a float controlled water feeder in which the float is readily adjustable to vary the effective water level.

A further important object of the invention is the provision in a water feeder of valve mechanism and float control mechanism therefor, which are so constructed and arranged that a very shallow body of water is all that is required to operate the valve.

Another object of the invention is the provision in such a water feeder of a scale agitator forming a part of the valve mechanism for agitating and removing any scale which may be deposited therein.

Another object of the invention is the provision of an automatic water feeder which will function to supply the required amount of water to a boiler or the like and will be wholly unaffected in its operation by the usual surging within the boiler.

Numerous other objects and advantages of the invention will be apparent as it is better understood from the following description, which, when taken in connection with the accompanying drawing, discloses a preferred embodiment thereof.

In the drawing:

Figure 1 is a vertical sectional view through a furnace boiler showing a device embodying the features of the instant invention operatively associated therewith;

Fig. 2 is a detail vertical sectional view of the water feeder device of Fig. 1; and

Fig. 3 is a perspective view of the baffle box used in the installation of Fig. 1.

Referring more particularly to the drawing, reference numeral 11 indicates in general a furnace boiler of any desired construction, which is shown herein as a low pressure steam boiler having an outer wall or casing 12, to the outer surface of which is secured a coating of suitable insulative material 13. A water feeder embodying the features of the instant invention is indicated generally by reference numeral 14, and is

shown in Fig. 1 mounted on the boiler 11 for maintaining constant the water level therein.

The water feeder 14 comprises a hollow, cylindrical shell or casing 15 which is provided with a suitable threaded portion on its outer surface 16 at each end thereof. When installed on the boiler 11, the threaded portion at the inner end of the casing 15 is screwed onto a suitable tapped aperture in the wall 12 of the boiler, the casing 15 extending through the insulative material 13. An outer casing member or cover 16 is provided with a circumferential flange 17 at its inner end which is adapted to be secured to the shell 15 by a suitable union or nut 18. A partition plate 19 is mounted at the outer end of the shell 15, and is rigidly secured between the latter and the flange 17 by the union 18. One or more suitable gaskets or packing washers 21 may be interposed between the partition plate 19 and the casing numbers 16 and/or 15 to insure a leak-proof connection therebetween.

The outer casing or cover member 16 is provided with a suitable tapped flange 22 within which the inner end of a water supply pipe or tubing 23 may be threaded. Intermediate its ends, the cover member 16 is provided with a pair of longitudinally spaced, inwardly extending, circumferential ribs 24. A removable screen 25, which is preferably made of Monel metal, is positioned interiorly of the cover member 16 and is adapted to be retained therein by the inwardly extending ribs 24. The outer casing or cover member 16 and the partition plate 19 define a water inlet chamber 26 which is supplied by the pipe or tubing 23. Any scale or other foreign matter carried by the water as it enters the chamber 26 will be caught by the screen 25 and deposited in the outer end of the chamber.

Rigidly secured in any suitable manner to the partition plate 19, and extending through an aperture provided therein, is a hollow valve member 27 which is provided with an inner bore 28 and an enlarged outer bore 29. The bores 28 and 29 are separated by an interiorly disposed annular flange 31 which is formed integrally with the body portion of the valve member 27 and is provided with a valve seat 32 on its inner surface. The valve member 27 is provided with a pair of diametrically opposed apertures 33 and 34 which communicate with the inner bore 28 and function as a spillway, and vent or relief opening, respectively.

A movable valve rod 35 is positioned within the bore 28 of the stationary valve member 27, and is provided adjacent its outer end with a seat 55

portion 36 adapted to engage against the seat 32 to cut off communication between the inlet chamber 26 and the interior of the shell 15. The outer end of the valve rod 35 terminates in a reduced portion 37 which is adapted in the operation of the valve rod to agitate and remove any scale which may be deposited within the valve member 27 adjacent the valve seat 32. The valve members 27 and 35 are preferably made of nickle silver to prevent corrosion thereof, although any other suitable material may be employed.

The inner end of the valve rod 35 terminates in an enlarged portion 38 which is slotted longitudinally to slidably embrace the outer end of a lever 39. The valve rod 35 and the lever 39 are pivotally connected by a pin 41. The stationary valve member 27 is provided with a pair of inwardly extending bracket arms 42 which are formed integrally therewith or rigidly secured thereto in any suitable manner. The outer end of the lever 39 is slidably disposed between the bracket arms 42 and is pivotally connected thereto by a pin 43. The pivot pins 41 and 43 are preferably made of Monel metal, although any other suitable material may be employed. The inner end of the lever 39 is rigidly secured to the outer end of a rod 44 by an adjustable thumb-screw 45. The inner end of the rod 44 is rigidly secured in any suitable manner to a hollow float 46 which is preferably made of copper, although any other suitable material may be employed.

As shown in Fig. 1, when the water feeder 14 is mounted on the boiler 11, the float 46 extends into the interior of the boiler and is disposed within and in spaced relationship to a baffle box member 47. The baffle box 47 is open at its top and outer end, and is provided at its outer end with a plurality of flange members 48 which are adapted to be rigidly secured in any suitable manner to the inner surface of the wall 12 of the boiler. The bottom of the baffle box 47 is provided with an aperture 49 which provides communication between the interior of the baffle box and that of the boiler 11 below the normal water level therein, the upper end of the baffle box being positioned above the normal working level of the water.

In the operation of the above described device, water is supplied to the inlet chamber 26 of the water feeder 14 by the pipe 23. Assuming an initial installation, the water will flow through the bores 29, 28 of the stationary valve member 27, through the spillway 33 and the casing 15 to the interior of the baffle box 47, and through the aperture 49 to the lower portion of the boiler 11. When the water within the boiler 11 and the baffle box 47 has reached the predetermined working level, the float 46 will have been moved upwardly to its position of Fig. 2. In such upward movement of the float, the valve rod 35 will be moved outwardly relative to the stationary valve member 27 by the lever 39 to engage the seat portion 36 of the rod with the seat 32 of the stationary valve member to cut off the supply of water to the boiler. The particular water level at which the float 46 will thus function to close the valve mechanism may be varied by adjusting the vertical position of the float through the agency of the screw 45.

As the water within the boiler 11 is transformed into steam, the water level will fall, which causes the float 46 to move downwardly about the pivot

43. As will be apparent from Fig. 2, the relative positions of the pivot pins 41 and 43 are such that only a slight downward movement of the float 46 is necessary to move the valve rod 35 inwardly away from the valve seat 32 to admit water from the inlet chamber 26 to the interior of the boiler, as above described. Consequently, water will be fed slowly and substantially constantly to the boiler so that the water therein will be maintained at a predetermined level. The vent 34 is provided to insure a smooth flow of water into the boiler and to break any vacuum which might form within the shell 15.

Due to the aperture 49 in the lower wall of the baffle box 47, the water level in the baffle box will be the same as that within the boiler 11, the baffle box 47 functioning to eliminate the effect of surging within the boiler upon the float 46. Without the baffle box 47, the surging of the water which normally takes place within the boiler would cause undesirable movements of the float 46. This would result in overfeeding of water to the boiler, but such faulty operation of the water feeder 14 is prevented by the baffle box 47 which retains a relatively calm body of water within which the float 46 is disposed. The baffle box 47 may also be cast integrally with the casing 12.

From the above description of the water feeder 14, it will be readily apparent that it may be used to automatically supply water to humidifiers of any desired type, expansion tanks and the like. It is particularly adapted for use with devices in which it is desired to maintain only a very shallow body of water, since a very slight vertical movement of the float 46 will function to open or close the valve mechanism 35, 27.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

In combination with a vertically disposed wall of a boiler, or the like, having a tapped aperture therein, a water feeder for automatically maintaining a constant water level in the boiler, comprising a hollow shell screwed into said tapped aperture, a cover member mounted on said shell and disposed exteriorly of said boiler wall, a partition plate disposed between said cover member and said shell to define a water inlet chamber with said cover member, valve mechanism mounted on said partition plate for controlling the flow of water from said inlet chamber to the interior of said boiler through said shell, a valve operating lever pivotally mounted interiorly of said shell for substantially vertical movement, and a float adapted to be disposed interiorly of the boiler to be moved vertically by the water therein and adjustably secured to said lever to operate said valve mechanism in accordance with a selected water level in said boiler, the cross-sectional dimensions of said float being less than those of said shell to facilitate insertion thereof through said aperture.

WILLIAM J. WOOLLEY.
